METHOD AND MACHINE FOR MAKING PAPER TUBES

Filed Oct. 12, 1928

2 Sheets-Sheet 2

UNITED STATES PATENT OFFICE

WILLIAM R. WILLAUER, OF SPARTANBURG, SOUTH CAROLINA

METHOD AND MACHINE FOR MAKING PAPER TUBES

Application filed October 12, 1928. Serial No. 312,193.

This invention relates to that class of paper-tube manufacturing in which sheets of paper are curled into cylindrical shape, with their adjacent edges overlapping and pasted permanently together, and an object of this invention is to provide a simple and inexpensive machine for curling and pasting the tube, the securing of the overlapped edges of the tube being done in such manner that the joint is virtually a welded joint, to thus make the seam inseparable and in fact stronger than the remainder of the body of the tube, as more fully hereinafter set forth.

In the drawings—

Fig. 1 is a side elevation of an apparatus for carrying out my method;

Fig. 2 is a plan view thereof;

Fig. 3 is a vertical sectional view of the apparatus;

Fig. 4 is a horizontal sectional view of the apparatus;

Fig. 5 is a horizontal sectional view taken on the line 5—5 of Fig. 3;

Fig. 6 is a vertical sectional view taken on the line 6—6 of Fig. 4;

Fig. 7 is a horizontal sectional view of the completed paper-tube.

Referring to the drawings annexed by reference-characters, 10 designates a base-plate mounted on a suitable frame and adapted to support a cylindrical vertical core consisting of a front stationary semi-cylindrical member 11 and a rear semi-cylindrical section designated 12, this latter section being vertically movable with respect to the base 10, for the purpose of collapsing the core in removing the curled blank. The vertically-movable section 12 is hingedly connected to the front stationary section by means of pairs of links 13, arranged in such manner that, when the movable section 12 rests, by gravity, on the base-plate 10, the links will be substantially horizontal, so that, when the movable section is at rest, the cylindrical core will be completed and so that when the movable section 12 is raised it will automatically, bodily move toward the front stationary section and thus collapse the core sufficiently to remove the shaped paper

Any suitable means may be used for raising the movable section 12. I have shown a fluid-pressure cylinder 14 whose combined inlet and outlet valve 15 is operable by means of an arm 16 connected to a rod 17 which extends to the front part of the machine for convenient operation by the foot or hand of the attendant. With this device, or any equivalent mechanism, the movable section may be raised to collapse the core and, after the curled sheet is removed, it will be dropped back in place on the base.

The forward side of the front, stationary section 11 is heated along its front vertical side by means of a tube 18 connected at its upper end to a steam-supplying-pipe 19 and at its lower end to an outlet-pipe 20. The paper sheet, designated by the numeral 21, is curled around the core 11—12 by means of a pair of semi-circular plates 22 hinged at the rear of the core to a vertical pintle 23 supported on an adjacent part of the frame. These two plates are made hollow for the reception of steam for heating them, the steam being supplied to these plates through the medium of suitable flexible pipes 24. These plates 22 reach nearly around the core, leaving a comparatively narrow space at the front side of the core for the reception of a vertical pasting-bar 25 which, when in place between the ends of the plates 22, completes the cylindrical curling means.

The two semi-cylindrical curling- or bending-plates 22 are swung forwardly and backwardly on the pintle 23 in any suitable manner. I have shown the following mechanism for doing this: Upon a slidable bar 26 I fasten a yoke 27 whose arms extend forwardly and are connected by links 28 to the plates 22, said rod 26 being slidable back and forth by a foot-operated angle-lever 29 connected to the rod by means of a link 30, the pedal-end of this angle-lever extending to the front of the machine, where it will be convenient for the operator to manipulate it by means of his foot. A retractile spring 31, shown in Fig. 1, is employed to normally pull upwardly on the pedal-end of the angle-lever 29 and thus normally open the curling-plates.

22. To hold the curling-plates in closed position, upon the core, I employ a latch device 32, or I may depend upon the pressure of the foot of the operator alone.
- 5 In curling the sheet 21, the curling-plates are allowed to swing outwardly and backwardly to the position shown in dotted lines in Fig. 4; then the sheet is slipped down vertically between the curling-plates and the 10 section 12 of the core, which section at that time rests on the base 10; then the curling-plates are swung forwardly to thus curl the sheet 21 around the core with its vertical edges in overlapped relation, as shown in Fig. 15 4; paste is then applied to the overlapped parts of the sheet and the sealing-bar 25 is forced toward the adjacent face of the core.
- To operate the sealing-bar, I connect the same to a pair of piston-rods 33 connected to 20 pistons working in cylinders 34. I supply steam or compressed air to these cylinders in any suitable manner to first move the sealing-bar forwardly into sealing position and then move it away from the core to release the 25 sealed cylindrical sheet. For this purpose, I provide a valve 35 in the steam-supply pipe which controls the entrance and exit of fluid to the branch-pipes 36 leading to the forward end of the cylinder and the branch-pipes 37 30 leading to the rear end of the cylinder. Any other suitable means may be employed for forcibly pressing the sealing-bar 25 against the sheet wound on the core and for retracting it therefrom to enable the pasted completed 35 cylinder to be removed from the core. The sealing-bar 25 is made hollow for the reception of steam supplied to it through a flexible pipe 38.
- After the cylindrical sheet is thus shaped 40 and pasted and the back core-member 12 is raised to collapse the core, it may be desirable to employ some device for loosening the paper cylinder from the core, as in some cases it may stick to the surface of the front stationary 45 core-section 11. For this purpose, I may use a fork 39 mounted on the base 10 and having fingers 40 adapted to engage under the lower edge of the paper cylinder, adjacent the overlapped seal, and provide a piston-rod 41 operable vertically by a piston working in a cylinder 42, this cylinder being provided with a valve 43 operable by an arm 44 connected to the aforesaid rod 17, whereby the forked ejector 39 may be raised and lowered at will. A 50 lost-motion slot 45 is provided between the arm 44 and the arm 17, so that the ejector-piston in cylinder 42 will be elevated immediately after the movable section 12 of the core is elevated. The valves 15 and 43 will, of 55 course, be so constructed as to release the fluid from the pistons when the rod 17 is again pulled forwardly, to thus permit the ejector-fork 39 and the core-section 12 to return to normal position.
- 60 Paste is desirably applied to the overlapped edges of the paper cylinder after the cylinder is curled around the core. The paper I prefer employing is of a kind which softens under heat, i. e., a sulphur-impregnated paper, and I prefer putting the sealing-bar 70 25 under sufficient heat and pressure to virtually "weld" the overlapped joint, i. e., soften the paper and press the overlapped parts together so intimately that the joint is virtually eliminated. I use a casein waterproof paste of well-known make, so that the paste under the action of heat and pressure entirely disappears into the body of the paper-sheet. In Fig. 7, the completed paper-cylinder is shown. It will be observed that the lines of the joint 80 have disappeared and that the paper is slightly thickened at the place of jointure. Even this extra thickness may be entirely eliminated by increasing the pressure, as the pressure will sufficiently condense the overlapped portions to make the wall of the cylinder at the jointure approximately the thickness of the wall at other points in the cylinder. I propose using these welded paper-cylinders 85 for shipping ice-cream, etc., where a waterproof paper having a permanent, inseparable waterproof joint is needed. In my experiments, I have found that with sufficient heat and pressure I can make the overlapped edges of the sheet become virtually one, the heat 90 serving to soften the paper sufficiently to permit the pressure to coalesce the overlapped parts and to cause the casein paste to be entirely absorbed in the overlapped parts of the sheet and thus virtually disappear, leaving no 95 layer of paste between the overlapped parts. 100
- In accordance with the provisions of the patent statutes, I have herein described the principle of operation of my invention, together with the apparatus which I now consider to 105 represent the best embodiments thereof, but I desire to have it understood that the apparatus disclosed is only illustrative and that the invention can be carried out by other means. 110 Also, while it is designed to use the various features and elements in the combinations and relations described, some of these may be altered and others omitted and some of the features of each modification may be embodied in the others without interfering with 115 the more general results outlined, and the invention extends to such use. For instance, it will be understood, of course, that the core as well as the sealing-bar 25 may be heated electrically instead of by steam, as illustrated 120 in my present drawings.
- Reaction between the sulphur and the paper and the casein paste at 230° F. brings about a combination of sulphur and casein to produce casein hydrolytic products. Since 125 the medium, namely, casein paste, is an alkaline one, some of the sulphur would be present as alkaline sulphide. It has been found that alkaline sulphites (and also sulphides to a less degree) increase the heat coagulability 130

or heat gel formation of proteins and likewise lower the coagulation temperature. The result is that the sulphur in the paper causes the casein to act just the reverse of its natural chemical action. Casein glue is recognized as a very slow-setting water-proof glue, and its use with a sulphur-impregnated paper causes not only a quicker setting but also a stronger adhesion in addition to waterproofness.

10 What I claim as new is:

1. In a paper-tube forming machine, a core, a pair of swinging bending-plates and means for operating them, a pasting-bar adapted to enter between the ends of said bending-plates and press toward the core, and means for actuating this pasting-bar.

2. In a paper-tube forming machine, a core, a pair of swinging bending-plates and means for operating them, a pasting-bar adapted to enter between the ends of said bending-plates and press toward the core, and means for actuating this pasting-bar, means being provided whereby the pasting-bar and the core are heated at the time of pressure on the joint.

3. In a paper-tube curling machine, a core having a longitudinally-movable section, means for moving this section to collapse the core, a pair of swinging semi-circular bending-sections, a pasting-bar adapted to enter between the ends of said sections and press against the overlapped joint of the enclosed paper-tube, and means for forcing this bar against the joint, means being provided whereby the core and the pasting-bar and said swinging sections are heated.

4. In a paper-tube forming machine, a core, a pair of swinging bending-plates and means for operating them, a pasting-bar adapted to enter between the ends of said bending-plates and press toward the core, and means for actuating this pasting-bar, an ejector mechanism being provided for slidingly separating the formed and pasted tube from the core.

5. The method herein described of forming seamless paper-tubes consisting in curling a sheet made of paper impregnated with a composition softenable under heat to cause the adjacent edges thereof to overlap, applying waterproof paste to the overlapped portions to form a joint, and applying heat and pressure to the pasted portions to cause the paste to impregnate the overlapped portions and weld said overlapped portions into an integral relation.

In testimony whereof I hereunto affix my signature.

60 WILLIAM R. WILLAUER.
